UNITED STATES PATENT OFFICE.

FRANK MORRISON, OF CLEVELAND, OHIO.

COMPASS-CORRECTING DEVICE.

SPECIFICATION forming part of Letters Patent No. 769,870, dated September 13, 1904.

Application filed March 16, 1903. Serial No. 147,979. (No model.)

To all whom it may concern:-

Be it known that I, FRANK MORRISON, a citizen of the United States of America, residing at Cleveland, in the county of Cuyahoga and State of Ohio, have invented certain new and useful Improvements in Compass-Correcting Devices; and I hereby declare the following to be a full, clear, and exact description of the invention, such as will enable others skilled in the art to which it pertains to make and use the same.

This invention relates to improvements in compasses.

The object of this invention is to provide means for correcting the variations in a compass caused by the proximity of bodies which exert a magnetic force or influence on the needle, tending to divert or draw the needle from its true position relative to the magnetic poles of the earth.

My invention therefore consists in providing means for supporting one or more correcting-magnets on the bowl of the compass, so that the changes in position of the compass-bowl as it swings on its supports will but slightly change the relative positions of the correcting-magnets and the needle of the compass, and therefore the force exerted by the correcting-magnets on the needle will be approximately constant.

My invention further consists in providing means for adjusting the magnets on the compass-bowl so as to increase or decrease the influence of the correcting-magnets on the needle.

My invention also consists in the features of construction and combination of parts, as illustrated in the drawings and hereinafter described in the specification and pointed out in the claim.

In the accompanying drawings, Figure 1 is a top plan of a compass provided with my improved device. Fig. 2 is a section on line 22, Fig. 1. Fig. 3 is a section on line 33, Fig. 2. Fig. 4 illustrates two sizes of correcting-magnets used in my device.

Again referring to the drawings, *a* represents the bowl of the compass, in which the needles *b* are mounted in the usual manner. The bowl *a* is mounted so as to swing verti-

cally in a ring *c*, which is similarly mounted in the top of the binnacle *d*. Around the rim of the bowl *a* of the compass is arranged a collar *e*, preferably formed of spun brass, in order that it may be light and thin, so as not to interfere in any way with the movement of the bowl in its regular mounting. In this collar *e* are formed a number of screw-holes *e'*. In the rim of the bowl *a* are formed series of screw-holes *a'*, and by turning the collar *e* on the rim of the bowl *a* the screw-holes *e'* can be made to register with the holes *a'*, and the collar can thus be adjusted circumferentially on the bowl *a* of the compass. Screws *e*² are provided for securing the collar *e* on the bowl *a*. On the collar *e* are arranged three plates *f*, preferably ninety degrees apart, on each of which is mounted a vertical frame comprising two posts *f'* and *f''* and a cross-plate *f*³. In each frame is arranged an endless screw *f*⁴, secured in bearings in the plates *f* and *f*³. The end of the screw *f*⁴ which projects through the plate *f*³ is preferably squared, as at *f*⁵, so that it may be engaged by a key or other device for turning it.

A bracket *g*, which is provided with a screw-threaded bore *g'*, corresponding to the screw *f*⁴, is arranged on each of the said screws *f*⁴ so as to travel up and down thereon when the screw is turned in one direction or the other. A screw *g*⁴ is provided for locking the bracket *g* on the screw *f*⁴. To each bracket *g* is secured a small horizontally-arranged tube *g*², the ends of which are closed by means of caps *g*³, which are preferably arranged to screw on the respective ends of the tube. Each of the tubes *g*² forms a receptacle for holding one or more correcting-magnets *n*. These correcting-magnets are graded according to their magnetic strength, so that by properly selecting one magnet or grouping two or more magnets and placing them in a tube *g*² any desired degree of magnetic influence or strength can be obtained.

A weight *h* is preferably secured on the collar *e* opposite the central plate *f*, so as to balance the bowl.

The operation of this device is as follows: The collar *e* is first adjusted on the rim of the

bowl of the compass, preferably in such a position that the central receptacle for the correcting-magnets will be perpendicular to the needles when the needles are in their true 5 north and south positions, and the other two receptacles will then be parallel with the needles. After the compass has been mounted in its proper position on the vessel the bow thereof is pointed to the north, and the compass is then corrected for the north. This is 10 accomplished by trying different grades of magnets in the receptacle until the north poles of the needles are approximately brought to their true position. After the proper magnets 15 have been placed in the receptacle the receptacle can be adjusted vertically, so as to increase or decrease the influence exerted by the magnets within the receptacle on the needles of the compass, thereby making it 20 possible to complete the correction with the greatest accuracy. When the compass has been corrected for the north, the vessel is turned so that the bow thereof points to the west, and the compass is corrected for the

west in a similar manner, after which the vessel is turned so that the bow points toward the east, and the compass is corrected for the east in the same way.

What I claim is—

The combination with the bowl of a compass, of a collar arranged to encircle the rim of said bowl, frames arranged on said collar, endless screws mounted in said frames, brackets arranged on said screws so as to be actuated by the rotation of said screws, tubes secured to said brackets, magnets arranged in said tubes and means for closing the ends of said tubes, substantially as described and for the purpose set forth.

In testimony whereof I sign the foregoing 40 specification, in the presence of two witnesses, this 10th day of March, 1903, at Cleveland, Ohio.

FRANK MORRISON.

Witnesses:

VICTOR C. LYNCH,
G. M. HAYES.
